UNITED STATES PATENT OFFICE

MYRON B. HAMMOND, OF BRIDGEPORT, CONNECTICUT, ASSIGNOR TO THE THOS. P. TAYLOR COMPANY, OF BRIDGEPORT, CONNECTICUT, A CORPORATION OF CONNECTICUT

SANITARY PAD SUPPORTER BELT

Application filed January 11, 1932. Serial No. 585,843.

The present invention relates to a sanitary pad supporter belt, and has for an object to provide a device of this character which will be of very simple construction, economical to manufacture, and capable of meeting the exacting requirements of such devices in a highly efficient and satisfactory manner. Another object is to provide a device of this character which will be inconspicuous and comfortable in use, will adapt itself to the natural configuration of the body without wrinkling or bulging, will yield freely to the various movements of the body, and at the same time will reliably support the sanitary pad in its proper position under all conditions without binding, chafing, or irritation.

A further object is to provide relatively wide tab portions, front and rear, having vertical expansibility, and which are integrally formed with respect to a relatively narrow elastic belt portion, and to this end I propose, in the illustrated exemplary embodiment of my invention, to employ two lengths of relatively narrow elastic webbing arranged side by side and cross-stitched together for a short distance at each end, the cross stitching being so arranged that it will yield in a longitudinal direction and at the same time will permit free expansion and contraction of the longitudinal elastic threads of the webbing.

Another object is to provide such a device in which the elastic webbing is free of transverse stitching which would tend to cut the elastic threads and impair uniform expansion and contraction, and also to so arrange the webbing that it will lie flat on the body at all points and retain its proper position under the varying strains and pulls to which such devices are subjected.

Other objects are to provide a device of this character which is free of metal parts, will lend itself to convenient and compact packaging, and will fit various sizes of wearers over a relatively large range.

With the above and other objects in view an embodiment of the invention is shown in the accompanying drawing, and this embodiment will be hereinafter more fully described with reference thereto and the in-

vention will be finally pointed out in the claims.

In the drawing:—

Fig. 1 is a plan view of the device, according to the present exemplary embodiment of the invention.

Fig. 2 is an enlarged plan view of one end portion, and showing the same in its normal position when not being used.

Fig. 3 is a similar plan view showing the end tab portion extended and the belt portions at an angle to the tab portion, this being their relative position when in use.

Fig. 4 is a perspective view showing the manner of assembling the end portion during manufacture.

Fig. 5 is a perspective view showing the completed end portion.

Fig. 6 is an enlarged transverse sectional view, taken along the line 6—6 of Fig. 5.

Fig. 7 is a perspective view showing the device in position upon the wearer.

Fig. 8 is a perspective view of a modified form of end tab.

Fig. 9 is a perspective view showing the tab illustrated in Fig. 8 secured by a modified arrangement of stitching.

Similar reference characters indicate corresponding parts throughout the several figures of the drawing.

Referring to the drawing, the supporter belt, according to the illustrated exemplary embodiment of the invention, comprises two equal lengths of elastic webbing 10—10 arranged side by side and secured together for a short distance at each end by a longitudinally extending line of cross-stitching 11, the extent of this stitching defining the length of the elastic end tab portion. A folded tab end 12 is secured at each end by transverse stitching 13, and is adapted to carry a safety pin 14, as shown in Fig. 1, for attaching the sanitary pad or napkin. The tab end 12 is preferably formed of a rectangular piece of cloth, folded in along its longitudinal edges and then folded upon itself, as clearly indicated in Fig. 4. As shown in Fig. 8 this tab may also have its ends folded in, as at 16.

The elastic webbing 10 is of well known

type, having a plurality of longitudinally extending threads of rubber 15, as shown in Fig. 5, the rubber threads at each edge being somewhat larger in diameter than the 5 intermediate threads, and the weave of the webbing being such that it has free expansion and contraction longitudinally. According to my invention the relatively wide elastic end portions, formed as integral continuations of the relatively narrow intermediate belt portions, will also have free expansion and contraction longitudinally. To this 10 end the cross-stitching 11 is preferably of zig-zag form adapted to freely expand and 15 contract longitudinally, as shown in Fig. 3, and in connecting the edges of the webbing is carried between the edge rubber thread and the next adjacent rubber thread so that there 20 is no impairment to the free elastic action of the webbing, and the chance of cutting the rubber threads and thus damaging the webbing is eliminated. It will thus be seen that the relatively wide end tab portions and the 25 relatively narrow belt portions are freely elastic from end to end of the device, and there is a complete absence of transverse seams, non-elastic inserts and metal parts, such as have been found in devices of this 30 nature heretofore in use. I am thus enabled to obtain a device which will be uniformly smooth at all points and free from objectionable bulges and wrinkles, and which at the same time will yield to every movement 35 of the body and snugly conform to its natural configuration. As the narrow elastic belt portions are extended at an angle to the relatively wide elastic tab portion as shown in Figs. 3 and 6, the natural and uniform stretch given to the webbing in use will allow the 40 material to assume a relatively sharp angle at the junction of the belt and tab portions while at the same time remaining flat, so that there will be no puckering or bulging at these points. 45 When not in use the device is in the form of a flat straight strip as shown in Fig. 1, and may be very conveniently packed in a neat and compact package.

The stitching 13 is illustrated as of the 50 same type as the stitching 12, particularly as this type of stitching will not cut the rubber threads at the ends of the webbing, but it will be understood that any suitable stitching may be employed at this point. For instance, in 55 Fig. 9 I have shown ordinary machine stitching 17, the ends of the tab being shown as folded in at 15, in this embodiment. The arrangement of the tab 12 and the transverse stitching securing it to the webbing is such 60 that the pull exerted on the tab is distributed evenly to the elastic webbing.

I have illustrated and described preferred 65 and satisfactory embodiments of my invention, but it will be obvious that changes may be made therein, within the spirit and scope

thereof, as defined in the appended claims.

Having thus described my invention, what I claim and desire to secure by Letters Patent is:—

1. In a sanitary pad supporter, front and rear tab portions and belt portions comprising a pair of parallel strips of elastic webbing having parallel inner and outer edges and arranged side by side in the same plane and secured together at each end along their adjacent inner edges in parallel relation to their outer edges to form said tab portions of single thickness and being unsecured between said tab portions to form belt portions. 70

2. In a sanitary pad supporter, a front and rear tab portions and belt portions comprising a pair of similar parallel strips of elastic webbing having parallel inner and outer edges and arranged side by side in the same plane and secured together at each end along their adjacent inner edges in parallel relation to their outer edges to form said tab portions of double width and single thickness and being unsecured between said tab portions to 75 form belt portions of single width. 80

3. In a sanitary pad supporter, front and rear tab portions and belt portions comprising a pair of parallel strips of elastic webbing arranged side by side in the same plane and secured together at each end along their adjacent edges by longitudinally extensible stitching to form said tab portions and being unsecured between said tab portions to 95 form belt portions. 90

4. In a sanitary pad supporter, front and rear tab portions and belt portions comprising a pair of parallel strips of elastic webbing having longitudinally extending elastic threads, said webbing being arranged side by side in the same plane and secured together at each end along their adjacent edges by longitudinally extensible stitching to form said tab portions and being unsecured between said tab portions to form belt portions, said stitching extending transversely across said edges and through said webbing between said elastic threads. 100

5. In a sanitary pad supporter, front and rear tab portions and belt portions comprising a pair of parallel strips of elastic webbing having parallel inner and outer edges arranged side by side and secured together at each end along their adjacent inner edges in parallel relation to their outer edges to form said tab portions of single thickness and being unsecured between said tab portions to form belt portions, and end tabs secured transversely to said front and rear tab portions. 115

Signed at Bridgeport, county of Fairfield, 120 and State of Connecticut, this 19th day of December, 1931.

MYRON B. HAMMOND.
